UNITED STATES PATENT OFFICE

RALPH BERTSCHE, JR., OF ANDERSON, INDIANA, ASSIGNOR TO DELCO-REMY CORPORATION, OF DAYTON, OHIO, A CORPORATION OF DELAWARE

ENGINE STARTER

Application filed November 15, 1928. Serial No. 319,697.

This invention relates to starting apparatus for internal combustion engines, and particularly to the type of apparatus which comprises an electric motor, a pinion driven thereby and manually operable means for moving the pinion into mesh with the engine gear and then closing a switch for causing the motor to operate.

It is one of the objects of the present invention to provide improved means for substantially fully engaging the motor pinion and the engine gear prior to closing the motor switch in order to eliminate breakage of gear teeth which has been found to occur owing to failure to move the motor gear into substantial engagement with the engine gear before the motor is operated.

Further objects and advantages of the present invention will be apparent from the following description, reference being had to the accompanying drawings, wherein a preferred embodiment of one form of the present invention is clearly shown.

In the drawings:

Fig. 1 is a fragmentary view, partly in longitudinal section, showing an embodiment of the present invention, the various parts being in normal position.

Fig. 2 is a sectional view on the line 2—2 of Fig. 1.

Fig. 3 is a sectional view on the line 3—3 of Fig. 2.

Fig. 4 is a diagrammatic, fragmentary, side view of the apparatus just after the motor pinion has been registered for meshing with the engine gear but just prior to movement of the motor pinion into mesh.

Fig. 5 is a sectional view on the line 5—5 of Fig. 4.

Fig. 6 is a view similar to Fig. 4, showing the pilot portion of the motor pinion in engagement with the engine gear.

Fig. 7 is a plan view of a sheet metal blank used to form a member of the mechanism which connects the foot pedal with the motor pinion.

Fig. 8 is a view similar to Fig. 4, showing the condition of the apparatus while cranking the engine.

Fig. 9 is a sectional view on the line 9—9 of Fig. 8.

Fig. 10 is a view similar to Fig. 4 but showing the motor pinion disconnected from the engine but the pedal operated lever still in position for closing the motor switch.

Referring to the drawings, the electric motor comprises a field frame 20 which is secured to gear housing or frame 21 adapted to be attached to the flywheel gear housing of the en-

gine to be started. The engine is not shown but is represented as having a flywheel gear 22 with which a pinion driven by the motor is adapted to engage for purposes of cranking the engine. This pinion comprises a pilot portion 23 and a main driving portion 24.

These portions are connected together in such a way that there may be a limited amount of longitudinal movement between them and also so that their teeth are always in alignment. This connection is provided by longitudinal splines 25 on the hub 26 of the pilot pinion 23, which splines engage with similar splines 27 and are provided internally of the driving pinion 24.

The pilot pinion 23 is normally maintained in spaced relation to the driving pinion 24 and in advance of the driving pinion with respect to the flywheel gear 22 by a spring 28 which presses at one end against the hub 26 of the pilot pinion 23 and

at the other end against the hub 29 of the driving pinion 24. The spring 28 is normally compressed to certain degree, and separation of the pinion 23 from the pinion 24 is limited by

a wire split ring 30 received by a suitable annular groove in the hub 26 of the pinion 23 and so located as to engage with an annular shoulder 31 provided internally of the pinion 24.

The pinion 24 is connected with its hub 29 with a tubular portion 32 which encloses the spring 28 and which is provided with holes 33 through which suitable tools may be introduced manipulating the split ring 30 so that it may be assembled with or may be removed from the hub 26 of the pilot pinion.

The pinion members are slidable along the armature shaft 35 of the electric motor. This shaft is supported at its ends by bearings, one of which is shown at 36 and is attached to the frame 21. The pilot pinion hub 26

is supported by a bearing 37 which is attached to the frame 21.

The pilot pinion hub 26 is supported by a bearing 38 which is attached to the frame 21.

slides along a smooth portion of the shaft 35, and the hub 29 of the driving pinion 24 is internally spirally broached so as drivingly to be engaged by helical splines 36 provided by the shaft 35. The hub 29 is normally supported by those portions of the shaft splines 36 which have a lesser outside diameter than other shaft spline portions. These spline portions of lesser diameter are located between interrupted conical shoulder portions 36^a and 36^b as shown particularly in Fig. 3, and these portions of lesser diameter are designated by numeral 36^c as shown in Figs. 2 and 3. It is therefore apparent that the shoulder portions 36^a provide obstructions which tend to prevent accidental movement of the motor pinion into engagement with the engine gear especially while the engine is running or the vehicle vibrating while not preventing the connection of the motor pinion with the engine gear by pedal operation. As shown particularly in Fig. 2, the hub 29 of the driving pinion 24 is provided with a mass 37 which is not symmetrically arranged with respect to the shaft. The purpose of this mass is to assist in preventing rebound of the motor pinion from normal position into engagement with the engine gear after it has been demeshed from the engine gear and before the motor shaft ceases turning. It is apparent that since the hub 29 is non-symmetrically weighted that it will, while rotating, tend to crowd its lighter side against the shaft spline portions 36^c with a pressure which corresponds to the unbalanced centrifugal forces acting upon the material comprising the pinion hub 29. Therefore, although there may be a tendency for the motor pinion to rebound into mesh with the engine gear while the shaft 35 is rotating, this tendency is overcome due to the fact that the unbalanced centrifugal forces acting upon the pinion hub 29 tend to lock the latter between the interrupted spline shoulders 36^a and 36^b.

The pedal operated mechanism for moving the motor pinion portions 23 and 24 into mesh with the engine gear comprises a pedal operated lever 40 and a pusher sleeve 41 attached to a pusher sleeve hub 42 which is slidable along the shaft 35 and is adapted to engage one end of the pinion hub 29 as shown particularly in Fig. 3. The pedal lever 40, which is operated by a pedal rod 43 and which is pivoted upon a bolt 44 attached to the frame 21, is connectable with the pusher sleeve 41 by means which may be disconnected from the pusher sleeve automatically before the engine becomes self-operative.

The means which connects the pedal lever with the pusher sleeve comprises a stud 45 attached to the lower end of the lever 40 and projecting into a somewhat triangular shaped opening 46 provided in the sleeve 41. This opening 46 is so shaped that the pusher sleeve

41 will be provided with an edge surface 47 which is located in a plane making preferably a small angle with a plane which is transverse to the axis of the motor shaft as shown particularly in Fig. 7 which shows the sheet metal blank 41^a which is formed into a cylinder to provide the sleeve 41. The opening 46 is shaped also so as to provide a recess 48 which normally receives the stud 45 and to provide an edge surface 49 adapted to cammingly engage the stud 45 for a purpose to be described later.

For a purpose to be described, it is desirable to have the pusher sleeve 41 frictionally connected with the pinion tube 32. This is accomplished by providing the pusher sleeve 41 with a spring pressed plunger 50 slidable within a tubular guide 51 attached to the sleeve 41 and urged by a spring 52 toward the pinion tube portion 32. Normally, as shown in Fig. 3, the plunger 50 extends into a shallow annular groove 53 provided by the pinion 24 but does not bottom in the groove since it is held spaced from the bottom of the groove due to the fact that a flange 54 on the plunger 50 engages the outer end of the guide 51. When, during the operation of the mechanism to mesh the motor pinion with the engine gear, the driving pinion member 24 is withdrawn from the pusher sleeve 41 as shown in Fig. 8, the plunger 50 will frictionally engage the tubular portion 32 of the pinion 24 in order to frictionally connect the pusher sleeve 41 therewith. This frictional connection is due to the engagement of the inner end of the plunger 50 with the tubular portion 32 and also due to the fact that the spring 52 tends to increase the friction between the tubular portion 32 and an arcuate insert 55 which is attached to the sleeve 41 and which partly encircles the tubular portion 32 as shown in Fig. 2.

The pedal lever 40 is normally retained in the position shown in Fig. 1 by a spring 60 received in a tubular recess 61 provided by the frame 21 and urging a plunger 62 against the lever 40 so as to tend to move it clockwise. This spring also tends to apply braking action to the armature shaft 35 due to the fact that it tends to urge the hub 42 of the pusher sleeve 41 toward the left as viewed in Fig. 1 and into engagement with a plate 63 which is mounted to slide along the shaft 35 but is prevented from rotating by reason of the fact that it has a portion 64 which straddles a stationary bolt 65. The shaft 35 carries a floating brake disc 66 located between the plate 63 and a metal brake disc 67 attached to the shaft 35. It is therefore apparent that the spring 60 when released will urge the brake plate 63 against the brake disc 66 and the latter against the brake disc 67. In this way the motor shaft 35 is quickly stopped after a starting operation has been performed. It is desirable to stop the motor shaft quickly

in order that the starting operation may be quickly repeated in case of a false start.

Operation

- 5 To start the engine, the pedal 43 is pressed downwardly in order to cause the lever 40 to move counterclockwise so that the stud 45 will engage the edge surface 47 of the pusher sleeve 41 so that the pusher sleeve will move 70 toward the right, thereby moving the pusher sleeve hub 42 against the left hand end of the hub 29 of the driving pinion 24. Continuing the motion of the pedal 43 downwardly, the pilot pinion 23 will be moved 75 into engagement with the engine gear teeth 22, as shown in Fig. 4. In case gear tooth abutment occurs preventing further movement of the pilot pinion 23 into mesh with the engine gear 22, by continuing the pedal 43 downwardly the driving pinion 24 will be 80 caused to move spirally along the shaft 35 due to the fact that its hub 29 is drivingly connected with the shaft splines 36. While the driving pinion member 24 is thus spirally moving the pilot 23 will be rotated so as to move into meshing registration with the engine gear 22. Figs. 4 and 5 show the condition of the apparatus just at the instant prior to registering the pilot pinion 23 with 85 the engine gear teeth 22. After the pilot pinion 23 has been registered for meshing with the engine gear teeth 22, the pilot pinion will be quickly moved into mesh with the engine gear 22 due to the fact that the spring 28, which has been compressed beyond its 90 initial state as shown in Fig. 5, has been released in order quickly to move the pilot pinion 23 from the position shown in Fig. 5 to that shown in Fig. 6. Thus the pilot pinion is fully meshed with the engine gear before the motor switch is closed. The pilot pinion does not move any further toward the right as shown in Fig. 6 due to the fact that it engages snap ring 70 received by an 95 annular groove 71 provided in the shaft 35. 100
- 45 By continuing the movement of the pedal 43 still further downwardly, a stud 80 carried by the lever 40 is caused to engage the operating plunger 81 of a switch enclosed within a housing 82 and operating to connect the motor with a source of current. When the switch is closed as shown in Fig. 8, the motor will operate to turn the shaft 35 in a clockwise direction as viewed looking in the direction of the arrow 83 or as viewed from the right in Fig. 8. This operation of the shaft 35 will cause the driving pinion 24 to be advanced into mesh with the engine gear as shown in Figs. 8 and 9. Since the pilot pinion 23 has been meshed with the engine gear before the driving pinion 24 is meshed therewith, the driving pinion will be located 115 in meshing registration with the engine gear so that there will be no difficulty in moving 120 the main driving pinion into mesh with the

engine gear. As the driving pinion member 24 is advanced into full mesh position, the spring 28 will again be compressed beyond its initial state and will tend to resist movement of the pinion 24 into engagement with the pinion 23 and thereby tend to lessen the shock of such engagement. 125

After the pinion 24 has been moved into mesh with the engine gear 22 and against the pilot pinion 23, continuing the rotation of the shaft 23 will cause the pinion members 23 and 24 to rotate with the shaft and to crank the engine through the gear 22. While the engine is being cranked, the end thrust due to the spiral spline connection is transmitted from the pinions to the shaft through the snap ring 70 and from the shaft to a thrust washer 85 adapted to bear against a machined surface 86 provided by the frame 21. 130

During the cranking operation, the pinion tube 32 will be withdrawn from the pusher sleeve 41 so that the plunger 50 will become operative to assist in frictionally connecting the pusher sleeve with the rotating shaft 35, 135 due to the frictional connection between the sleeve and the pinion 24 already explained. When this takes place, the sleeve 41 will be dragged by the shaft in a clockwise direction as viewed from the right in Fig. 8 and will 140 retract the notch portion 48 of the opening 46 from the lever stud 45 and cause the camming edge surface 49 to engage the stud 45 thereby causing the sleeve 41 to move from the position shown in Fig. 6 to the position shown in Fig. 8. Therefore before the engine becomes self-operative, the pusher sleeve hub 42 will have been moved back to normal position so as not to hinder automatic demeshing of the motor pinion from the engine 145 gear when the engine starts. 150

After the starting operation, the operator may release the pedal 43 to permit the spring 60 to return the parts to normal position as shown in Fig. 1 and to apply the brake to the shaft 35. As the spring 60 is permitted to expand it will move the lever stud 45 toward the left to cause it to engage the oblique edge surface 49 and thereby cause the pusher sleeve 41 to be rotated from the position shown in Fig. 10 to the position shown in Fig. 1. As the lever 40 returns to normal position, the switch operating stud 80 will be retracted from the plunger 81 so as to permit a spring 87 to return the operating plunger 81 to switch open position. 155

While the form of embodiment of the present invention as herein disclosed, constitutes a preferred form, it is to be understood that other forms might be adopted, all coming 160 within the scope of the claims which follow.

What is claimed is as follows:

1. Engine starting apparatus comprising, in combination, a drive pinion movable endwise into mesh with a gear connected with

the engine to be started, a pilot pinion adapted to mesh with the engine gear, manually operable means for causing the pilot pinion first to mesh with the engine gear and then 5 the drive pinion, and a connection between the pilot pinion and drive pinion such that the drive pinion will be guided into mesh with the engine gear.

2. Engine starting apparatus comprising, 10 in combination, a drive pinion movable endwise into mesh with a gear connected with the engine to be started, a pilot pinion adapted to mesh with the engine gears, manually operable means for causing the drive pinion 15 to rotate while being advanced toward the engine gear, and means so connecting the drive pinion and pilot pinion that rotation is imparted to the pilot pinion while the drive pinion is advancing toward the engine 20 gear in order that the pilot pinion will be turned into meshing registration with the engine gear.

3. Engine starting apparatus comprising, 25 in combination, a drive pinion movable endwise into mesh with a gear connected with the engine to be started, a pilot pinion adapted to mesh with the engine gears, means normally maintaining the pilot pinion in advance of the drive pinion relative to the engine 30 gear, manually operable means for turning the pilot pinion and for moving the pinions endwise, and connections between the pinions permitting relative endwise movement but causing the pinions to turn together.

35 4. Engine starting apparatus comprising, in combination, a drive pinion movable endwise into mesh with a gear connected with the engine to be started, a pilot pinion adapted to mesh with the engine gear, manually 40 operable means for applying yielding pressure to the pilot pinion to urge the same toward the engine gear and for turning the pilot pinion into meshing registration with the engine gear, and a connection between the 45 pilot pinion and drive pinion such that the drive pinion will be guided into mesh with the engine gear.

5. Engine starting apparatus comprising, 50 in combination, a drive pinion movable endwise into mesh with a gear connected with the engine to be started, a pilot pinion adapted to mesh with the engine gear, manually operable means for applying yielding pressure to the pilot pinion to urge the same toward the engine gear and for causing the drive pinion to rotate while being advanced toward the engine gear, and means so connecting the drive pinion and pilot pinion that rotation is imparted to the pilot pinion 55 while the drive pinion is advancing toward the engine gear in order that the pilot pinion will be turned into meshing registration with the engine gear.

6. Engine starting apparatus comprising, 60 in combination, a drive pinion movable end-

wise into mesh with a gear connected with the engine to be started, a pilot pinion adapted to mesh with the engine gear, means yieldingly maintaining the pilot pinion in advance of the drive pinion relative to the engine gear, 70 manually operable means for turning the pilot pinion and for moving the pinions endwise, and connections between the pinions permitting relative endwise movement but causing the pinions to turn together. 75

7. Engine starting apparatus comprising, 80 in combination, a drive pinion movable endwise into mesh with a gear connected with the engine to be started, a pilot pinion adapted to mesh with the engine gear, a yielding member for transmitting endwise movement from the drive pinion to the pilot pinion and normally maintaining the pilot pinion in advance of the drive pinion relative to the engine gear, manually operable means for turning the pilot pinion and for advancing the drive pinion toward the engine gear, and connections between the pinions permitting relative endwise movement but causing the pinions to turn together. 85

8. Engine starting apparatus comprising, 90 in combination, a drive pinion movable endwise into mesh with a gear connected with the engine to be started, a pilot pinion adapted to mesh with the engine gear, a spring located between the pinions for transmitting endwise movement from the drive pinion to the pilot pinion and normally maintaining the pilot pinion in advance of the drive pinion relative to the engine gear, manually operable means for turning the pilot pinion and for advancing the drive pinion toward the engine gear, and connections between the pinions permitting relative endwise movement but causing the pinions to turn together. 95

100 9. Engine starting apparatus comprising, in combination, a drive pinion movable endwise into mesh with a gear connected with the engine to be started, a pilot pinion adapted to mesh with the engine gear, a spring located between the pinions for transmitting endwise movement from the drive pinion to the pilot pinion and normally maintaining the pilot pinion in advance of the drive pinion relative to the engine gear, manually 105 operable means for causing the drive pinion to rotate while being advanced toward the engine gear, and means so connecting the drive pinion and pilot pinion that rotation is imparted to the pilot pinion while the drive pinion is advancing toward the engine gear in order that the pilot pinion will be turned into meshing registration with the engine gear. 110

115 10. Engine starting apparatus comprising, 120 a drive shaft, a drive pinion and a pilot pinion mounted to slide along the shaft into mesh with a gear of an engine to be started, connections between the pinions permitting relatively longitudinal movement and caus- 125

ing the pinions to rotate together, a spring normally maintaining the pilot pinion in advance of the drive pinion, and manually operable means for moving the pinions toward the engine gear and for causing the pilot pinion to turn into meshing registration with the engine gear.

11. Engine starting apparatus comprising, a drive shaft, a drive pinion and a pilot pinion mounted to slide along the shaft into mesh with a gear of an engine to be started, connections between the pinions permitting relatively longitudinal movement and causing the pinions to rotate together, a spring normally maintaining the pilot pinion in advance of the drive pinion, connections between the shaft and drive pinion such that longitudinal movement of the drive pinion along the shaft is accompanied by rotary movement of the drive pinion, and manually operable means for moving the drive pinion along the shaft.

12. Engine starting apparatus comprising, a drive shaft, a drive pinion and a pilot pinion mounted to slide along the shaft into mesh with a gear of an engine to be started, connections between the pinions permitting relatively longitudinal movement and causing the pinions to rotate together, a spring surrounding the shaft and located between the pinions and normally maintaining them in spaced relation and manually operable means for moving the pinions toward the engine gear and for causing the pilot pinion to turn into meshing registration with the engine gear.

13. Engine starting apparatus comprising a drive shaft, a drive pinion and a pilot pinion mounted to slide along the shaft into mesh with a gear of an engine to be started, connections between the pinions permitting relatively longitudinal movement and causing the pinions to rotate together, a spring surrounding the shaft and located between the pinions and normally maintaining them in spaced relation, connections between the shaft and drive pinion such that longitudinal movement of the drive pinion along the shaft is accompanied by rotary movement of the drive pinion, and manually operable means for moving the drive pinion along the shaft.

14. Engine starting apparatus comprising a motor, means for connecting the motor with the gear of an engine to be started and including a drive pinion movable axially into mesh with the gear of an engine to be started and provisions whereby the drive pinion will be automatically demeshed when the engine starts; a pilot pinion located between the drive pinion and engine gear; manually operable means for causing the pilot pinion first to mesh with the engine gear and then the drive pinion, and a connection between the pilot pinion and drive pinion such that the drive pinion will be guided into mesh with the engine gear.

15. Engine starting apparatus comprising a motor, means for connecting the motor with the gear of an engine to be started and including a drive pinion movable axially into mesh with the gear of an engine to be started and provisions whereby the drive pinion will be automatically demeshed when the engine starts; a pilot pinion located between the drive pinion and engine gear; manually operable means for causing the drive pinion to rotate while being advanced toward the engine gear, and means so connecting the drive pinion and pilot pinion that rotation is imparted to the pilot pinions while the drive pinion is advancing toward the engine gear in order that the pilot pinion will be turned into meshing registration with the engine gear.

16. Engine starting apparatus comprising a motor, means for connecting the motor with the gear of an engine to be started and including a drive pinion movable axially into mesh with the gear of an engine to be started and provisions whereby the drive pinion will be automatically demeshed when the engine starts; a pilot pinion located between the drive pinion and engine gear; manually operable means for applying yielding pressure to the pilot pinion to urge the same toward the engine gear and for turning the pilot pinion into meshing registration with the engine gear, and a connection between the pilot pinion and drive pinion such that the drive pinion will be guided into mesh with the engine gear.

17. Engine starting apparatus comprising a motor, means for connecting the motor with the gear of an engine to be started and including a drive pinion movable axially into mesh with the gear of an engine to be started and provisions whereby the drive pinion will be automatically demeshed when the engine starts; a pilot pinion located between the drive pinion and engine gear; a yielding member for transmitting endwise movement from the drive pinion to the pilot pinion and normally maintaining the pilot pinion in advance of the drive pinion relative to the engine gear, manually operable means for turning the pilot pinion and for advancing the drive pinion toward the engine gear, and connections between the pinions permitting relative endwise movement but causing the pinions to turn together.

18. Engine starting apparatus comprising a motor, means for connecting the motor with the gear of an engine to be started and including a drive pinion movable axially into mesh with the gear of an engine to be started and provisions whereby the drive pinion will be automatically demeshed when the engine starts; a pilot pinion located between the drive pinion and engine gear; a spring located between the pinions for transmitting endwise movement from the drive pinion to the pilot pinion and normally maintaining

the pilot pinion in advance of the drive pinion relative to the engine gear, manually operable means for causing the drive pinion to rotate while being advanced toward the engine gear, and means so connecting the drive pinion and pilot pinion that rotation is imparted to the pilot pinion while the drive pinion is advancing toward the engine gear in order that the pilot pinion will be turned into meshing registration with the engine gear.

19. Engine starting apparatus comprising a motor, a shaft driven thereby and having helical splines; a drive pinion connected with said splines and movable endwise along the shaft into mesh with a gear of an engine to be started; a pilot pinion movable along the shaft in advance of the drive pinion; longitudinal spline connections between the pinions; a spring for maintaining the pinions separated; and manually operable means for moving the pinions toward the engine gear and for rotating them to facilitate meshing.

In testimony whereof I hereto affix my signature.
